UNITED STATES PATENT OFFICE.

EDWARD L. LOWE, OF PALO ALTO, CALIFORNIA.

BURNER FOR INTERNAL-COMBUSTION ENGINES.

Application filed December 29, 1922. Serial No. 609,776.

To all whom it may concern:

Be it known that I, EDWARD L. LOWE, a citizen of the United States, residing in the city of Palo Alto, county of Santa Clara, 5 State of California, have invented a new and useful Burner for Internal-Combustion Engines, of which the following is a specification.

My invention relates to a novel construction of a burner and its adjuncts for internal combustion engines, whereby in lieu of gasoline as a fuel, I am enabled by my 10 novel construction to employ the cheapest and heaviest grades of hydro-carbons or oils 15 whose cost approximates but a few cents per gallon, as compared with the more expensive lighter hydrocarbons, such as gasoline and the like.

In order to describe my novel burner for 20 oil burning internal-combustion engines, I will give certain fundamental facts and requirements with respect to the combustion of fuel oil which form the basis of this invention.

25 (1) At the present time, an ordinary internal combustion engine fuel oil has generally a flash point between 150° F. and 200° F. and a fire test in the neighborhood of 250° F. or 300° F.

(2) Air when compressed to 200 pounds per square inch is raised in temperature to about 670° F. Lower as well as higher compressive pressures have corresponding temperatures. It will be noted that the temperature of 670° is far in excess of that actually required to burn ordinary fuel oil. If now 30 this temperature can in some way be utilized to ignite oil of combustion, a new era in internal combustion engine construction will be inaugurated.

My novel burner which is the subject of this application comprises a device which may be used on engines with compressive pressures lower than those used in engines 45 of the Diesel type, and is applicable to engines using a light fuel for starting only, as well as engines which have no such provision, depending in either case entirely 50 upon the compressive pressures for which the engine is designed. My experiments have indicated that with a compressive pressure of about 200 pounds per square inch ordinary fuel oil may be ignited from a 55 cold start, and that an engine with much lower compressive pressure will operate

satisfactorily on the same grade of oil, but must be started on a lighter fuel with higher flash and fire test.

The advantages of my novel device over 60 present methods reside in its extreme simplicity of construction, its freedom from carbon depositions and its satisfactory functioning with comparatively low compressive pressures. Its freedom from carbon depositions is accomplished by ignition and combustion taking place without contact of the fuel oil with parts at either extremely 65 high temperatures or parts at low temperatures. Extremely high temperatures as met with in the hot bulb engines have a tendency to decompose or "crack" the oil of combustion instead of vaporizing it and with consequent deposition of carbon. When the 70 oil of combustion deposits on cool surfaces, it does not vaporize and a carbon deposit results.

To the above ends, my invention consists 75 of a novel construction of a burner for internal combustion engines, comprising a 80 plurality of concentrically arranged cylindrical metallic ferrules, thimbles or sleeve-like members, which for convenience of manufacture are made separate so as to be readily assembled or disconnected if desired, 85 said thimbles being clamped or positioned by novel mechanism within a pocket or passage in the engine cylinder communicating with the compression chamber.

It further consists of a novel construction 90 of a burner for an internal combustion engine composed of an outer flange or supporting member, a plurality of concentric metallic cylindrical thimbles, ferrules or sleeve-like members so collocated that a cylindrical central combustion chamber of relatively 95 large area is provided within the inner thimble, while the annular space between the two thimbles comprises a thin or restricted 100 annular ignition chamber.

It further consists of a novel construction 105 of a burner composed of cylindrical, concentric thimbles or sleeve-like members, which are in the shape of thin metallic cylinders, the inner thimble or cylinder being preferably shorter than the outer thimble, and novel means being provided for positioning said burner in a pocket or passage in the engine cylinder in communication 110 with the compression chamber.

It further consists of other novel features

of construction, all as will be hereinafter fully set forth.

For the purpose of illustrating my invention, I have shown in the accompanying drawings, a form thereof which is at present preferred by me, although it is to be understood that the various instrumentalities of which my invention consists is not limited to the precise arrangement and organization of these instrumentalities as herein shown and described.

Figure 1 represents a vertical sectional view of a novel burner and its adjuncts for an internal combustion engine, certain of the parts being shown in elevation.

Figure 2 represents, on an enlarged scale and in detached position, a perspective view of the outer thimble, ferrule or sleeve-like member of the burner.

Figure 3 represents a perspective view of the inner thimble, ferrule or sleeve like member of the burner.

Figure 4 represents a section on line 4—4 of Figure 1.

Similar numerals of reference indicate corresponding parts.

Referring to the drawings, 1 designates a cylinder of an internal combustion engine, which is provided with the piston 2, having a curved or convex head 3, which reciprocates in the piston chamber 4, the wall 5 of the latter being curved to conform to the contour of said piston.

The passage 6 which leads from the upper portion of the piston chamber communicates with the chamber 7 which is controlled by the air intake valve 8, air entering the chamber 7 through the passage 9, said passage 6 also communicating with the chamber 10 having the exhaust pipe 11, said exhaust chamber 10 being controlled by the exhaust valve 12.

The piston 2 and the valves 8 and 12 are actuated by any suitable or conventional mechanism, which it is unnecessary to describe in detail.

13 designates a passage or pocket in a wall of the cylinder 1, within which is positioned the burner 14, which is composed of the outer thimble, ferrule or thin cylindrical member 15, which has at its upper portion the flange 16 whose outer portion is bevelled as indicated at 17, and is also provided with a peripheral bottom shoulder 18, whereby the under side of said flange is supported upon the upper edge or wall of the pocket or passage 13. The flange 16 has an inner counterbore 19 upon which is seated the flange 20 of the inner thimble, ferrule or thin cylindrical member 21, the upper portion of which is provided with ports 22.

It will be noted that when the parts seen in Figures 2 and 3 are telescopically assembled to form my novel burner, that the lower edge 23 of the inner thimble or cylin-

der is preferably above the lower edge 24 of the outer thimble or cylinder 15, and, the two cylinders being arranged concentrically, it will be apparent that a thin annular restricted chamber 25 is formed between the cylinders 15 and 21, said thin annular chamber serving as an ignition chamber and being in communication through the ports 22 with the upper portion of the central relatively larger combustion chamber 26, which is formed within the inner thimble of cylinder 21. The burner members 15 and 21 being telescopically assembled as seen in Figure 1, are clamped or retained in their assembled position by means of the clamping plate 27, which has a bottom bevelled wall 28, it being apparent that the walls 17 and 28 when the parts are assembled form a triangular seat for the gasket 29, the manner of assembling said walls and gasket being understood from Figure 1, and the parts being securely held in assembled position upon tightening the bolts or the like 30.

The clamping plate 27 or cap is provided with a central seat 31 in which the flanges 16 and 20 of the burner members are collocated, and said plate 27 has the passage 32 therethrough, into which the fuel oil is admitted through the inlet pipe 33, the latter being connected to a suitable oil pump.

It will be apparent that the burner members are composed of thin metallic ferrules or thimbles, which extend towards the compression space of the cylinder and have their ends opening thereto, said thimbles or cylinders having an air space between them.

It will be apparent that my novel manner of constructing and assembling the thimbles 21 and 15 to form the burner 14 results in a very simple and effective construction, whereby the parts can be readily assembled or disconnected for the purpose of inspection, replacement or repairs.

It will further be apparent that by my manner of clamping the burner members in position by the employment of the bevelled walls 17 and 28 and the gasket 29, collocated as seen in Figure 1, a very cheap and effective joint or seal is produced, and I am enabled by the single gasket construction shown to dispense with a plurality of such gaskets.

It will be apparent that the plate or cap 27 is of heavier metal or considerably thicker than the cylinders 21 and 15, whose upper ends are in contact therewith, and that consequently said cap is not so susceptible to changes of temperature as are said thimbles or cylinders and consequently acts as a temperature regulating member.

During the combustion stroke to be hereinafter referred to, this is a vital matter, as it is the only means provided to keep the thimbles below destructive temperatures.

I have found that it may be desirable under some conditions to introduce a liquid

or fluid into the thick cap 27, under which conditions I form a chamber 34 therein adapted for the reception of the liquid or fluid, said chamber being shown dotted in Figure 1 and its extent and contour being understood from Figure 4.

The liquid or fluid, as oil or water, can be introduced into said chamber 34 by means of the inlet pipe 35, and withdrawn therefrom through the outlet pipe 36, and, it will be apparent that if desired, the pipe 35 may communicate with the water jacket 37 of the engine cylinder.

It will be readily understood that the effect of the liquid contained in the chamber 34 will be to pre-heat the fuel as it passes through the passages 32, which may be desirable under certain conditions and when employing certain grades of fuel.

20 The operation is as follows:—

In order to start the engine it is only necessary to set it in motion or to turn it over, either by hand or by any one of the conventional methods now in use, and, in the following description, the term inward refers to the motion of the piston towards the crank shaft and outward refers to the direction of movement of said piston away from the crank shaft.

30 Assuming the piston to be in its inward position, it will be apparent that the piston chamber 4 has received a charge of air at or near atmospheric pressure, through the inlet 9, chamber 7 and passage 6, the valve 35 8 having been actuated by any suitable mechanism.

The first outward stroke of the piston into substantially the position seen in Figure 1, obviously compresses the air, with a consequent increase in its temperature. This air fills all the compression space and enters all spaces in and around the burner, this function or action being obviously effected since the ignition chamber 25, the combustion chamber 26 and the passage or pocket 13 are freely open to the compression space.

The following heat interchanges take place:—

50 The air in the space 13 relinquishes a portion of its heat to the jacket through the cylinder head wall 5, and a portion of said heat is absorbed by the outer thimble or cylinder 15.

A portion of the heat is also absorbed by the cap 27. In like manner, the air in the space 25 or ignition chamber relinquishes heat to the cylinders 15 and 21 and also to the cap 27. The air in the space or combustion chamber 26 relinquishes heat to the thimble or cylinder 21 and also to the cap 27.

By reason of the manner of assembling or collocating the burner elements, it will be evident that the cap 27 also receives heat from the thimbles or cylinders 21 and 15

by reason of its direct contact with them.

As the piston moves inwardly after the first compression stroke, the compressed air expands, losing its heat and the air in the spaces 13, 25 and 26, while cooling, receives heat from the thimbles or cylinders 15 and 21 and also from the cap 27, which, being made of metal, lose their heat less rapidly than the air.

When the piston reaches the end of its inward stroke, a fresh charge of air enters, and it moves outwardly again on its second compressive stroke. The burner and the air within it are still warm, so that the interchange of heat between the burner and the compressed air will be less than on the first stroke, but interchanges of heat take place in similar manner. On the third stroke, the interchanges will be less than on the second, and so on until the burner comprising the cylinders 15 and 21 reaches a temperature approaching that of the air of compression.

When this point has been reached, a charge of fuel is allowed to enter the burner through the passage 32, and the oil first appearing at the mouth of said passage 32, receives heat from its contact with the cap 27 and from the air in the space or combustion chamber 26. The heat given up by the air is immediately made up in part by radiation from the thimble 21 and cap 27, and is, in practice, sufficient to vaporize and ignite the charge.

The charge is supplied by a piston pump through the pipe 33, and its discharge into the burner continues over a fixed period of the cycle. The oil, therefore, reaching the burner after the initial flash burns upon its arrival within the burner and burns completely, leaving no residue or carbon deposit. I have found in practice that no fuel reaches the combustion space of the burner except in an incandescent state.

It will be readily appreciated that the ignition and burning of the charge materially alters the heat interchange that takes place subsequent to ignition. The thimbles or cylinders 15 and 21 are heated to a temperature in excess to that corresponding to the compressive pressure, and, in consequence upon each successive compression stroke, instead of receiving heat from the air of compression, they give heat to it, or in other words, said thimbles are cooled by the air of compression.

The burner therefore functions to maintain a reasonably even temperature, its design being such as to lend itself to this desired end.

It will be noted that, as heretofore explained, the cap 27 is of heavier metal than the thimbles 15 and 21, which are in contact with it, and consequently said cap is not so susceptible to quick changes in temperature.

as are said thimbles, said cap thus acting as a temperature regulating member.

During the combustion stroke, this is a vital matter, as it is the only means provided to keep the thimbles below destructive temperatures.

I have found from numerous experiments that my novel burner functions without overheating under all conditions of load or revolution, which indicates that a heat balance is reached by my novel construction which fulfills all requirements.

From the above it will be apparent that should it be desired to use a compression lower than that required to ignite low grade fuel oil by compression, when the engine is cold, a lighter fuel oil, with higher flash and fire test, may be used for starting, and after the burner has received heat from combustion, the light oil may be shut off and the lower grade oil turned on to the burner. It will then continue to function on the low grade oil, receiving and dispensing heat as described above.

It will be understood from the foregoing, that the ignition chamber 25 and the combustion chamber 26 are always filled with air during the period of compression. At or near the end of the compression stroke, fuel is slowly admitted through the passage 32 into the heated air, due to compression contained in the central combustion chamber 26. Due to the natural action of liquid fuel when subjected to heat interchanges, causing a partial "cracking" or separation of the lighter and heavier gases, the lighter gases naturally rise to the top of the combustion chamber 26, and the heavier gases remain suspended below the lighter gases in said combustion chamber, which now contains a fuel which has slowly been admitted, and due to heat interchanges has become gasified to a greater or lesser degree, and is now commingled with the air in the combustion chamber, heated by compression, which has caused the heat interchanges, between the thimbles and cap as above explained.

As stated, the lighter gases are now at the top of the combustion chamber due to natural causes. Also due to the fact that the lighter gases will ignite at a much lower temperature than the heavier gases, the series of ports 22 at the top of the combustion chamber 26 connecting with the outer thin ignition chamber 25 allow the lighter gases, when they begin to ignite, to come into contact with the pure air in the ignition chamber, and said pure air in the ignition chamber accelerates the burning of said lighter gases, which causes a very quick interchange of heat upon the cylinder 21 surrounding the combustion chamber. There is no explosion in my novel device at any stage of the cycle, but instead a slow progressive burning due to the fact that the oil is slowly

admitted, the initial burning taking place in proximity to the ports 22, and a portion of the initial flame is in the upper part of both the ignition chamber and combustion chamber. The burning of the gases progresses gradually downwardly and reaches the mouth of the burner communicating with the compression space of the cylinder, and the burning gases come in direct contact with the heated air in the compression space, which causes a complete combustion of the gases above the piston, which in turn effects the actuation of the latter.

While I have shown the preferred manner of forming and assembling the thin thimbles or burner elements 15 and 21 with respect to the cap or thickened plate 27, it will be evident that said burner elements may be otherwise constructed and assembled or secured to said cap, and positioned within the compression space, so that the proper coaction between these elements may be effected.

While I have described my novel burner as particularly adapted for utilizing the cheapest or heavier grades of fuel, it will be understood that the same construction of burner functions with equal efficiency with gasoline or any of the lighter grades of hydrocarbon, and it will further be noted, irrespective of the character or grade of fuel employed, I am enabled in my novel device to dispense with spark plugs, the carburetor and ignition system.

It is obvious that the thimbles constituting the burner elements may be of other shapes and lengths than that shown, and I have shown them in the present instance, as made cylindrical for the sake of convenience of construction.

It will also be understood that a plurality of thimbles or burners may be employed, if desired, to suit varying conditions or requirements.

When a plurality of the burners are employed, it will be evident that they may be disposed around or in the cylinder head in any desired arrangement which will produce the greatest efficiency.

While I preferably make the inner thimble shorter than the outer thimble, it will be apparent that the lengths of these thimbles may be proportioned differently from the construction shown, it being essential, however, that the central combustion chamber and the outer ignition chamber communicate at their upper and lower portions, the upper communication being had by the restricted ports 22.

My present invention is differentiated from the burner shown in my contemporaneously pending application, Serial No. 537,997, since the outer thimble or sleeve herein is open throughout its entire lower area, which facilitates the discharge of the

expansive medium upon the juxtaposed end of the piston.

It will now be apparent that I have devised a novel and useful burner for internal combustion engines, which embodies the features of advantage enumerated as desirable in the statement of the invention and the above description, and while I have, in the present instance, shown and described a preferred embodiment thereof which will give in practice satisfactory and reliable results, it is to be understood that such embodiment is susceptible of modification in various particulars without departing from the spirit or scope of the invention or sacrificing any of its advantages.

Having thus described my invention, what I claim as new and desire to secure by Letters Patent, is:—

20 1. In a device of the character stated, a burner composed of an outer sleeve, and an inner sleeve positioned within said outer sleeve, both of said sleeves being open and unobstructed at their lower ends, whereby an outer ignition chamber is formed between said sleeves open at its bottom, and a relatively large combustion chamber is formed within said inner sleeve, said chambers being in communication at their upper and lower ends.

25 2. In a device of the character stated, a burner composed of an outer sleeve, and an inner sleeve of less length than said outer sleeve positioned within said outer sleeve, whereby a relatively thin outer annular ignition chamber open at its bottom is formed between said sleeves, and a relatively large central combustion chamber is formed within said inner sleeve, the latter having ports 30 at its upper portion forming a communication between the upper portions of said chambers, and both of said sleeves being open and unobstructed throughout the entire area of their lower ends.

35 3. In a device of the character stated, a burner composed of an outer sleeve, and an inner sleeve positioned within said outer sleeve, and having its lower end terminating above the bottom of said outer sleeve, whereby a relatively thin annular ignition chamber open at its bottom is formed between said sleeves, and a relatively large central combustion chamber is formed within said inner sleeve, the latter having ports 40 at its upper portion forming a communication between the upper portions of said chambers and said outer sleeve being open and unobstructed throughout its entire area at its lower end, and a fuel nozzle discharging fuel into said combustion chamber at a point in proximity to said ports.

4. An insertible burner for internal combustion engines having an elongated central combustion chamber and an elongated 45 surrounding relatively thin ignition cham-

ber communicating therewith through restricted ports near its upper end, the remaining portion of said elongated ignition chamber being cut off from said combustion chamber, but communicating therewith at its lower end, said chambers being open and unobstructed throughout their entire lower area opening into the compression space.

5. A burner for engines of the slow combustion type, comprising a plurality of approximately concentric cylindrical sleeves separated from each other by an outer air space forming an ignition chamber opening into the compression space of the engine and a central combustion chamber formed within the inner sleeve and opening into said compression space and having restricted communication with said ignition chamber near one end, the opposite ends of said chambers communicating, and the outer sleeve being open and unobstructed throughout its entire lower area opening into said compression space.

6. An insertible burner for internal combustion engines, comprising a plurality of interfitted sleeves, one within the other, and separated from each other by an outer elongated air space forming a relatively thin ignition chamber, the inner sleeve containing the combustion chamber and having small ports near its outer end, said burner being adapted to be mounted in the wall of an engine cylinder, and said combustion chamber and ignition chamber communicating at their lower ends and opening into the compression space of said cylinder, said chambers being non-communicating throughout their length and open and unobstructed at their lower ends, and a support for said sleeves adapted to be secured to said cylinder.

7. In a device of the character stated, a burner composed of an outer sleeve and an inner sleeve positioned within said outer sleeve, both of said sleeves being open and unobstructed at their lower ends, whereby an outer ignition chamber is formed between said sleeves open at its bottom, and a relatively large combustion chamber is formed within said inner sleeve, said chambers being in communication at their upper and lower ends, in combination with a relatively thick cap in metallic contact with the upper ends of said sleeves, for securing the latter in position.

8. In a device of the character stated, a burner composed of an outer sleeve and an inner sleeve positioned within said outer sleeve, both of said sleeves being open and unobstructed at their lower ends, whereby an outer ignition chamber is formed between said sleeves open at its bottom, and a relatively large combustion chamber is formed within said inner sleeve, said chambers being in communication at their upper and lower

ends, in combination with a relatively thick cap in metallic contact with the upper ends of said sleeves, said cap having a chamber therein for the reception of a liquid and an opening therethrough for the admission of the fuel.

9. The combination of an engine cylinder, a hollow cap secured thereto and adapted to receive a liquid and having a fuel passage therethrough, a plurality of flanges in metallic contact with said cap and secured to said cylinder thereby, an outer thimble carried by one of said flanges and positioned in a passage within said cylinder, said outer thimble being open and unobstructed at its lower end, an inner thimble, secured to the other of said flanges, and positioned within said outer thimble, whereby there is formed a central combustion chamber, and an outer ignition chamber, said chambers being in communication at their opposite ends, and both of said chambers having an uninterrupted communication at their lower ends with the compression space of the cylinder.

10. The combination of an engine cylinder, a relatively thick cap secured thereto and having a fuel passage therethrough, an outer flange in metallic contact with said cap and having a thimble secured thereto open and unobstructed at its lower end, an inner flange seated in said outer flange and in metallic contact with said cap, an inner thimble carried by said inner flange and positioned within said outer thimble, and ports near the upper end of said inner thimble, there being a combustion chamber formed within said inner thimble and an ignition

chamber formed between said thimbles, said chambers communicating at their bottoms.

11. A burner for an internal combustion engine formed of an outer flange, an outer thimble secured at one end thereto and open and unobstructed at its opposite end, a counterbore in said outer flange, an inner flange seated in said counterbore and an inner thimble having ports near its flange end, secured to said inner flange and positioned within said outer thimble.

12. A burner for an internal combustion engine, formed of an outer flange, an outer thimble secured at one end thereto and open and unobstructed at its opposite end, an inner flange seated in said outer flange and an inner thimble secured to said inner flange and positioned within said outer thimble, and having restricted ports near its flange end, said inner thimble being shorter than said outer thimble.

13. A burner for an internal combustion engine, formed of an outer flange, an outer thimble secured at one end thereto and open and unobstructed at its opposite end, an inner flange seated in said outer flange, an inner thimble secured to said inner flange and positioned within said outer thimble, and having restricted ports near its flange end, said inner thimble being shorter than said outer thimble, and a relatively thick cap in metallic contact with said flanges for securing the latter to an engine cylinder.
